US00D923072S

(12) **United States Design Patent** (10) Patent No.: **US D923,072 S**
 Persson et al. (45) Date of Patent: ** *Jun. 22, 2021

(54) **MONITORING CAMERA**(71) Applicant: **AXIS AB**, Lund (SE)(72) Inventors: **Henrik Persson**, Lund (SE); **Fredrik Axelsson**, Loddekopinge (SE); **Andreas Hertzman**, Helsingborg (SE); **Gert Nilsson**, Sjöbo (SE); **Daniel Ahman**, Lomma (SE); **Mathias Walter**, Arlov (SE); **Morten Bergstrom**, Bjarred (SE)(73) Assignee: **AXIS AB**, Lund (SE)

(*) Notice: This patent is subject to a terminal disclaimer.

(**) Term: **15 Years**(21) Appl. No.: **29/633,780**(22) Filed: **Jan. 16, 2018****Related U.S. Application Data**

(63) Continuation of application No. 29/564,737, filed on May 16, 2016, now Pat. No. Des. 811,462.

(30) **Foreign Application Priority Data**

CLAIM

The ornamental design for a monitoring camera, as shown and described.

DESCRIPTION

FIG. 1 is a perspective view of a monitoring camera showing our new design;

FIG. 2 is a left side view thereof;
FIG. 3 is a top plan view thereof;

FIG. 3 is a top plan view thereof, FIG. 4 is a front elevational view

FIG. 4 is a front elevational view

FIG. 5 is a rear elevational view thereof; and,

FIG. 6 is a right side view thereof, and FIG. 7 is a bottom plan view thereof.

The broken lines shown in the drawing

the monitoring camera in which the design is embodied and form no part of the claimed design.
